UNITED STATES PATENT OFFICE

2,040,278

RHEOSTAT

David T. Siegel, Chicago, Ill.

Application April 29, 1935, Serial No. 18,785

15 Claims. (Cl. 201—55)

My invention relates to rheostats and potentiometers and particularly to novel features of construction in the contact arm, brush and the form of connection thereof with the operating shaft.

This application is a continuation in part of my application Serial No. 702,843 filed December 14, 1933.

As stated in the preamble, the object of my invention is to improve the construction of the movable elements of a rheostat, the particular improvements being pointed out in connection with the following detailed explanation.

The invention will be more readily understood by reference to the accompanying drawing in which

Fig. 1 is a plan view of a rheostat constructed in accordance with my invention;

Fig. 2 is a longitudinal section view through the construction shown in Fig. 1;

Fig. 3 is an assembly of the metal parts of the rheostat;

Fig. 4 is a perspective view of the porcelain sleeve constituting a part of the assembly;

Fig. 5 is an enlarged sectional view showing the core, brush and an end of the contact arm; and

Fig. 6 is a sectional view of the line 6—6 of Fig. 2.

The device of my invention includes a base 10 of porcelain or similar dielectric material, the base having a seat on which is seated the core 11, wound with resistance wire 12. The base, core and wire, with the exception of the contact face of the wire are coated with an enamel slip, indicated at 13, and baked to fuse the enamel.

The base is provided with an axial opening adapted to receive the operating shaft 14. An operating knob 15 is connected to one end of the shaft for rotating the same, the shaft being rotatably mounted within a metal sleeve 16, the outer end of which is threaded to receive the clamping nut 17. The sleeve is held against longitudinal movement on the shaft on one end by means of a split ring 18 that engages in a circumferential groove in the shaft and on the opposite end by means of a disc 19 having a projection 20, the disc being held in place by being pressed over the knurled or milled portion 21 of the shaft. The sleeve is held against rotation in the base by the following means: The axial recess in the base is somewhat enlarged at the point 22 and notches are provided in diametric opposite sides of the recess to engage with the projections 23 on a perforated washer 24.

This washer has a stop member 25 adapted to be engaged by the projection 20 to limit the turning movement of the shaft, the angular extent of the member 25 being selected to provide a predetermined sweep of the contact arm. The washer 24 also has a short projection 26 at the periphery of the opening therein, this last named projection engaging with a notch in the end flange 27 of the sleeve 16. In Fig. 3 I have shown the washer in dotted lines in such position that the projection 26 is about to enter the notch in the flange 27. Thus the sleeve is held against rotation while the shaft is permitted to freely rotate therein.

Mounted on the inner end of the shaft 14 is a porcelain sleeve 28 having a head 29 and diametrically opposite projections 30 from the head. The shank or body 31 of the sleeve is cylindrical in form and fits over the shaft 14. Notches 32 are provided in the head; the notches having communication with the axial opening in the sleeve. The outer end of the shaft 14 is upset or formed to extrude metal to form projections 33 that enter the notches 32 in the sleeve, this connection serving to prevent relative rotation between the shaft and sleeve.

The sweep arm or contact arm, as best shown in Figs. 1, 2, and 3, consists of a section of spring metal doubled on itself, the doubled portions having registering apertures of different size and shape. The straight or sweep portion 34 of the arm has an opening therein as shown in Fig. 1 that conforms to the contour of the head or driving hub 29 of the dielectric sleeve, the projections 30 on the sleeve serving as the means for effecting rotation of the arm. The shape of the opening is such that the arm is permitted to slightly move up and down, that is to oscillate on the point 35 as a center thereby securing the effect of a relatively long spring arm. The rebent portion 36 is flat as shown, and the aperture therein is substantially of the diameter of the cylindrical portion 31 of the sleeve. Thus the head 29 of the sleeve overlies the rebent portion. The purpose for this will be later described.

The outer end of the arm is bent down and a U shaped metal member 37 is placed transversely of the arm and riveted in place, the head 38 of the rivet projecting into the cup-like space formed as the result of the construction described. The head 38 constitutes the bearing for a brush 39 of novel composition. This brush is composed of graphite as a substantial ingredient and finely divided metal impregnated therein. Inasmuch as the brush is in direct contact with

the exposed surface of the resistance winding, its action in service is particularly satisfactory. The wire surface becomes polished and there is no tendency towards deterioration or wear. Whatever unevenness may occur in the contact surface is compensated by the capacity of the brush to rock on the round head 38 of the rivet. This capacity is permitted by reason of the use of a flexible cable 40 preferably composed of braided or twisted fine wire, the cable being imbedded in the brush, as shown in Fig. 5, and at its opposite end soldered as at 41 to a contact washer 42 that surrounds the cylindrical shank 31 of the dielectric sleeve. This washer has a projection 43 therein that engages a notch in the end of the rebent portion of the contact arm. This insures rotation of the washer with the arm. A coil spring 42a separates the washer and the flat rebent portion of the arm and provides for constant spring pressure tendency to hold the washer in electrical contact with the terminal member 44 that is seated on the base and held against rotation by means of the projection 45 thereon.

It will be noted that during assembly, or, if desired, at any time thereafter, the nut 17 is actuated and this serves to pull inwardly the shaft and the dielectric sleeve and to compress the spring 42a. This serves to resiliently hold the contact washer against the terminal member with a firm pressure. This is the only sliding contact between the brush and the terminal, all the other connections being permanent.

The contact arm and brush are electrically insulated from the shaft due to the interposition of the dielectric sleeve between the shaft and the contact members. The parts are so designed that stampings are used substantially entirely, and the devices will operate without the necessity for repairs for long periods of time. The relatively long resilient sweep arm, the graphite-metal brush mounted for rocking movement, the flexible direct connection between the brush and the terminal and the complete insulation of the described parts from the operating shaft, all contribute towards the production of a rheostat that will be free of trouble throughout long periods of use.

An important advantage in the construction shown is that of wide separation of the line and grounded parts of the instrument; in that regard I refer to separation in terms of distance superficially. For example the end of the shaft 14 is countersunk in the head of the insulating sleeve and the distance between the shaft and the contact arm, measured on the outside surface of the insulating sleeve is relatively great. This is likewise true at the opposite end of the sleeve.

Many of the features described herein are applicable to other forms of electrical instruments such as switches, etc. and I do not wish to be limited, except as indicated in the appended claims.

I claim:

1. In combination, a base, resistance wires supported on said base, a shaft in the base, a contact arm connected to the shaft, means providing a cup on the end of said arm, a projection being provided on the floor of said cup, a brush seated within said cup and bearing on said projection with capacity for rocking movement thereon, a terminal, and a connection between the terminal and brush, the connection being sufficiently flexible to permit said brush to rock.

2. In combination, a base, resistance wires supported on said base, a shaft in the base, a contact arm connected to the shaft and insulated

therefrom, means providing a cup on the end of said arm, a projection being provided on the floor of said cup, a brush seated within said cup and bearing on said projection with capacity for rocking movement thereon, a terminal and a connection between the terminal and brush, the connection being sufficiently flexible to permit said brush to rock.

3. In combination, a winding of resistance wire and means for supporting the same, a contact arm and means for rotating the same, a terminal, a contact member mounted to rotate on said terminal, a brush carried by said contact arm and separate therefrom, means for electrically connecting said brush to said contact member, said brush directly riding on said resistance winding and being composed of graphite as a substantial ingredient and metal impregnated therein.

4. In combination, a winding of resistance wire and means for supporting the same, a contact arm and means for rotating the same, a terminal, a contact member mounted to rotate on said terminal, a brush carried by said contact arm, a flexible conductor connecting said brush and said contact member, said brush riding directly on said resistance winding and being composed of graphite and finely divided metal impregnated therein.

5. In combination, a winding of resistance wire and means for supporting the same, a contact arm and means for rotating the same, a terminal, a contact member mounted to rotate on said terminal, a brush carried by said contact arm, a flexible conductor permanently connected to said brush and said contact member, said brush riding directly on the resistance winding and being composed of graphite as a substantial ingredient and finely divided metal impregnated therein.

6. In a rheostat, the combination of a base and resistance wires associated therewith, a shaft journaled in the base, a contact arm, a terminal carried by the base and spaced from electrical contact with said shaft and electrically connected to said arm, a sleeve composed of dielectric material telescoped over said shaft and having a projection and recess connection to prevent relative rotation, said sleeve overlying a portion of the contact arm to hold the same in position and having a projection and recess connection with the arm to effect the turning thereof.

7. In combination, a base and a resistance element associated therewith, a shaft journaled in the base, a contact arm, a terminal electrically connected to said arm, a sleeve composed of dielectric material carried by an end of said shaft and connected thereto for rotation therewith, said connecting means constituting a stop member for limiting rotation of said shaft and arm, said sleeve serving to space said terminal from the shaft, said sleeve projecting through an opening in said arm and serving as the means for transmitting the rotation of the shaft to the arm.

8. In combination, a base and a resistance element supported thereby, a shaft journaled in the base, a contact arm composed of spring material and doubled on itself to form a loop, the looped portion having registering openings of different diameters, a sleeve composed of dielectric material non-rotatively connected to the shaft and having a shank and an enlarged end, the shank of said sleeve extending through both openings in said arm and the enlarged end of the sleeve projecting through the opening of largest diameter in said arm and having non-rotative engagement therewith and overlying the material

surrounding the smaller opening in said arm and serving to hold said arm against axial displacement from the shaft.

9. In combination, a base and a resistance element supported thereby, a shaft journaled in the base, a contact arm composed of spring material and doubled on itself to form a loop, the looped portion having registering openings of different diameters, a sleeve composed of dielectric material having an axial opening to receive the end of the shaft and a lateral recess to receive a projection from said shaft said sleeve having a head being adapted to enter the larger of the registering openings in said arm and the projection on the head overlying the portion of said arm containing the opening of smaller diameter and serving to retain the arm against axial displacement on the shaft.

10. In a rheostat, the combination of a base and resistance wires associated therewith, a shaft journaled in the base, a contact arm, a terminal carried by the base and spaced from electrical contact with said shaft and electrically connected to said arm, a sleeve composed of dielectric material telescoped over said shaft and having a projection and recess connection to prevent relative rotation, said sleeve overlying a portion of the contact arm to hold the same in position and having a projection and recess connection with the arm to effect the turning thereof, and a pin carried by the shaft and adapted to engage limit stops on the base.

11. In a rheostat, the combination with a base and a winding of resistance wire supported thereon, a shaft carried by the base, a sleeve composed of dielectric material non-rotatively connected to an end of said shaft, said sleeve having a head, a contact arm composed of spring material, means on the outer end of said arm providing a contact surface for engagement with the resistance wire, the inner end of said arm being rebent, the arm and rebent portion of the arm having registering openings adapted to receive said sleeve, the opening in said rebent portion being of less diameter than the head on said sleeve, whereby said head overlies said rebent portion and retains said arm in place, and means preventing relative rotation between the arm and sleeve.

12. In a rheostat, the combination with a base and a winding of resistance wire supported thereon, a shaft carried by the base, a sleeve composed of dielectric material mounted on an end of said shaft and held against rotation relative thereto, said sleeve having a non-round head, a contact arm composed of spring material, means on the free end of said arm providing a contact surface for engagement with the resistance wire, the opposite end of said arm being doubled on itself to provide a U-shaped portion, said U-shaped portion being punched to provide registering openings, the opening in the upper part of the U-shaped portion being non-round to cooperate with said head, the opening in the lower part of said U-shaped portion being of less diameter than said head whereby said head overlies said last named portion of the arm and is prevented from separation from the shaft thereby.

13. In a rheostat, the combination with a base and a winding of resistance wire supported there-

on, a shaft carried by the base, a sleeve composed of dielectric material non-rotatively connected to an end of said shaft, said sleeve having a head, a contact arm composed of spring material, means on the outer end of said arm providing a contact surface for engagement with the resistance wire, the inner end of said arm being rebent, the arm and rebent portion of the arm having registering openings adapted to receive said sleeve, the opening in said rebent portion being of less diameter than the head on said sleeve, whereby said head overlies said rebent portion and retains said arm in place, means preventing relative rotation between the arm and sleeve, said rebent portion being transversely bent to provide for spring compression between said head and a support, and means acting on said shaft for inducing said compression.

14. In a rheostat, the combination with a base and a winding of resistance wire supported thereon, a shaft carried by the base, a sleeve composed of dielectric material non-rotatively connected to an end of said shaft, said sleeve having a head and a cylindrical portion, a terminal piece secured to the base and having a recess in its inner end axially arranged relative to the cylindrical portion of said sleeve, a contact washer also having a recess axially arranged relative to said sleeve and overlying and in electrical contact relation to said terminal piece, a brush engaging said resistance wire and connected to said contact washer, a contact arm composed of spring material and having its free end constructed to support said brush, the opposite end of said arm being rebent, the arm and rebent portion of the arm having registering openings adapted to receive said sleeve, and to hold said arm against rotation on said sleeve, the opening in the rebent portion being of less diameter than the head on the sleeve whereby said head overlies and clamps said rebent portion against said contact washer.

15. In a rheostat, the combination with a base and a winding of resistance wire supported thereon, a shaft carried by the base, a sleeve composed of dielectric material non-rotatively connected to an end of said shaft, said sleeve having a head and a cylindrical portion, a terminal piece secured to the base and having a recess in its inner end axially arranged relative to the cylindrical portion of said sleeve, a contact washer also having a recess axially arranged relative to said sleeve and overlying and in electrical contact relation to said terminal piece, a brush engaging said resistance wire and connected to said contact washer, a contact arm composed of spring material and having its free end constructed to support said brush, the opposite end of said arm being rebent, the arm and rebent portion of the arm having registering openings adapted to receive said sleeve and to hold said arm against rotation on said sleeve, the opening in the rebent portion being of less diameter than the head on the sleeve whereby said head overlies and clamps said rebent portion against said contact washer, said rebent portion being transversely bent to provide for spring compression between said head and said washer, and means acting on said shaft for inducing said compression.
